UNITED STATES PATENT OFFICE

2,627,603

BRASSIÈRE AND FRAMEWORK THEREFOR

Julius E. Lilienfeld, St. Thomas, V. I.

Application June 22, 1950, Serial No. 169,699

5 Claims. (Cl. 2—42)

1

This invention relates to a brassière.

Broadly, it is an object of the invention to provide a light-weight brassière which will stay positioned on the body without the help of shoulder straps, is inexpensive to manufacture and is freely accessible to air circulation.

More particularly, it is an object of the invention to make the resilient properties of the brassière frame take over the function of shoulder straps by providing a brassière which has a framework of resilient spring wire preset to a predetermined shape in combination with a fabric which provides form-giving breast coverings.

Another object is to provide means making the brassière adaptable to an asymmetrically developed female figure by an easily movable member.

A significant feature of the invention is that the said framework is so preset as to form a three dimensional curve, which means that the frame does not lie flat in a plane but is concave when looking at it from one side and convex when looking at it from the other side. It looks very much like a butterfly with partly folded wings. While the brassière is applied to the female figure, its design requires that the convex side of the frame be turned toward the wearer and then the resilient frame distorted until it fits in the position in which it is to be used. The geometrical feature of the latter arrangement is that any tangent plane to one loop is inclined to the corresponding plane of the other loop, the angle between the two said corresponding planes in the brassière positioned upon the wearer being substantially of a sign opposite to the angle between said tangent planes when the framework is released from said position.

For a fuller understanding of the nature and objects of the invention, reference is had to the following detailed description, in connection with the accompanying drawings, in which:

Fig. 1 is a front elevation of the brassière, the dot and dash lines showing one loop made larger than the other for use for asymmetric breasts.

Fig. 2 is a perspective view showing the framework in three dimensions.

Fig. 3 is an enlarged sectional view of the sleeve which forms the endless wire into two loops.

Fig. 4 is an enlarged front view of a modified sleeve provided with indentations to secure the relative position of the two loops.

Fig. 5 is an enlarged sectional view of the rod with the loose tubing around it.

Referring to the drawings, a resilient rod or wire 10, which may be of steel, Phosphor bronze, nickel chrome or other metal alloy, forms the resilient frame similar to the numeral eight. By presetting the frame, however, it is made to deviate from a plane figure and curve in the third dimension. One way to manufacture the frame

2

is to preset the wire prior to joining the ends by coiling it around a cylindrical mandrel whose diameter is determined by the amount of the intended "butterfly" effect. Next, the ends are joined and formed into the aforesaid figure eight-like shape. The latter shape is maintained by a sleeve through which the rod is passed twice in opposite directions and which may be in sliding relation to the frame so as to allow, if needed, an asymmetric arrangement between the two loops.

The frame does not lie flat in a plane but is actually concave when seen from one side and convex when seen from the opposite side so that it has somewhat the appearance of a butterfly with partly folded wings.

The wire frame is preferably made of .0045 to .0060 of an inch diameter by doubling up a length of approximately 37 inches of wire, then passing both ends through a sleeve 11 and then joining the ends of the wire 12 either by brazing or by force-fitting the sleeve over the ends or by any other well known means. The area about the joined ends can be manipulated into the aforesaid sleeve 11 so that it will be out of sight. The sleeve may be rigidly fixed upon the approximate central portion of the wire framework by indenting the same in a manner shown in Fig. 4, e. g., by indentations 13. Of course, numerous other means may be used to form the shape of the wire, to join the ends, and construct the sleeve suitably fitting the framework.

The wire framework may be covered with a tubular member of soft rubber or rubber-like material 18 which preferably has a bore substantially larger than the wire to cushion the frame upon the body, or coated with rubber by dipping it in a latex suspension and coagulating same upon the wire. The frame having thus been completed, the fabric 14 which may comprise elastic yarns, may then be applied to the framework, creating a pair of pockets to cover and support the breasts. A fabric may be used for the pockets which comprises a retiform base of substantially inelastic filaments in combination with a pattern of mutually non-intersecting form controlling elastic filaments crossing the pattern of said inelastic filaments, as disclosed in United States patent applications, Ser. Nos. 65,484 and 115,150 filed December 15, 1948, and September 12, 1949, respectively.

In Fig. 2 the framework is shown with a more pronounced dip between the pockets so that the gown of the wearer may be of deeper cut in the central portion thereof and may be worn without revealing the brassière.

In using the brassière, the wearer spreads the two loops in the form of the two wings of a butterfly with the convex side of the framework towards the body. The two loops of the frame-

work are then brought into contact with the body of the wearer by forcing them against the opposing resilient force of the preset framework. The brassière, after it has been brought into contact with the body, is then fixed in that position by tightening the back straps 15 and 16 and joining the same by hooks and eyes, snaps 17, or other well known means.

It is obvious that various changes and modifications may be made in the details of construction and arrangement of parts without departing from the general spirit of the invention.

I claim:

1. A strapless brassière comprising a single resilient wire element three dimensionally curved and projecting onto the vertical plane in the shape of two loops forming the figure 8, said loops being adapted to encircle the breasts of the wearer, and a body encircling band, means at the ends of said band for detachably joining the ends thereof, said body encircling band attached to the opposed vertices of the said figure 8, fabric attached to the said wire element and forming pockets over the openings of said loops, said wire element being prestressed to curve away from the wearer upon detaching the ends of said band.
2. The brassière according to claim 1, wherein the pockets are of an elastically expandable material.

3. The brassière according to claim 1, wherein the pockets are of a material comprising a retiform base of substantially inelastic filaments in combination with a pattern of mutually non-intersecting elastic filaments crossing said inelastic filaments.

4. The brassière according to claim 1, in which the resilient wire element is formed into the shape of the figure 8 by means of a sleeve through which said wire passes twice in opposite directions.

5. The brassière according to claim 1, in which the resilient wire element is formed into shape of the figure 8 by means of a sleeve through which said wire passes twice in opposite directions, said sleeve being in slidable relation to said wire.

JULIUS E. LILIENFELD.
